UNITED STATES PATENT OFFICE.

JOHN WILLIAMS QUYNN, OF PARKERSBURG, WEST VIRGINIA.

GOLF CLUB.

Application filed April 21, 1928. Serial No. 271,866.

This invention aims to provide a novel form of golf club, the same embodying the features of a lofting club and straight face of a driving club, the object of the invention 5 being to provide a club which will greatly increase distance when used in the rough or in a sand trap.

Another object of the invention is to provide a club which will not only pick up the 10 ball but one wherein the follow through will cause the club to drive the ball forwardly.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within 20 the scope of what is claimed without departing from the spirit of the invention.

Referring to the drawing:

Figure 1 is an end elevational view of a club constructed in accordance with the invention.

Figure 2 is a front elevational view thereof.

Figure 3 is a vertical sectional view through the blade.

Referring to the drawing in detail, the 30 blade is indicated generally by the reference character 5 and includes a lower lofting section 6, similar to the blade of a mashie, mashie niblick or the like to give the neces-

sary loft to the ball when struck with the club in getting out of rough or a sand trap. 35

Formed integral with the blade section 6 is a substantially vertical section 7 which is designed to give distance to the ball so that a person in using the club in the rough may not be restricted to the limited distance that 40 can be gotten with the use of a mashie, or mashie niblick, which are the clubs generally used in executing a golf shot in the rough or sand trap.

The club is of course provided with the 45 usual socket 8 extending from the body portion of the blade, in the usual manner and which socket receives the shaft 9 of the club, as clearly shown by the drawing.

From the foregoing it will be obvious that 50 when a club such as shown and described is used, the inclined blade section 6 will pass under the ball giving the ball the necessary loft to lift it out of the rough, while the blade section 7 which is substantially straight, 55 will contact with the ball on the follow through, giving the ball distance which is not possible with the usual lofting club.

I claim:

A golf club embodying a blade having an 60 inclined section for lofting a ball, and an integral vertical section extending from the upper edge of the inclined section.

In testimony that I claim the foregoing as my own, I have hereto affixed my signature.

JOHN WILLIAMS QUYNN.
